DIAPHRAGM ANNULUS WITH A SPRING THEREIN

William L. Hudson and Harold Lee, Fort Wayne, Ind., assignors to Tokheim Corporation, a corporation of Indiana

Application April 28, 1952, Serial No. 284,722

7 Claims. (Cl. 137—793)

This invention relates to a diaphragm device, especially a diaphragm pump, and to a diaphragm comprising a working annulus having opposite walls which are mechanically supported from each other, as by a helical spring annulus. In some respects, the invention is an improvement of the generic subject-matter of the co-pending application of Charles D. Hoover, Serial No. 89,448, filed April 25, 1949.

It is the primary object of our invention to provide a diaphragm device and a diaphragm therefor which will operate over a wide range of temperatures, especially at extremely low temperatures of the order of —65° F. It is an object of our invention to provide a diaphragm in which opposite walls are mechanically supported from each other in constantly convex position. It is an object of our invention to provide a diaphragm-device construction which will permit long full strokes while subjecting the diaphragm walls to minimum load-reaction stress, which will give a high suction lift, which will operate efficiently both on such long full strokes and on short partial strokes, which will give long diaphragm life, and which will facilitate use of diaphragm materials which are resistant to fluids that attack rubber-like materials. It is an object of our invention to provide such a diaphragm construction in which the working portion of the diaphragm is of leather or leather-like material.

Our invention is desirably embodied in a diaphragm device in which the diaphragm has a rigid central piston portion and a surrounding annular working portion, and in accordance with our invention, the working portion is provided with opposite outwardly-convex walls, desirably shaped to semi-circular section, and such walls are mutually supported in outwardly convex position by mechanical means disposed between them. The mutual supporting means is of generally toroidal shape to lie within the similarly shaped space between the opposite diaphragm walls. It is desirably formed of spring wire with adjacent elements thereof spaced somewhat from each other, and is most desirably formed as a helical spring with spaced convolutions and with its ends secured together to form a ring. When the support is a spring-like member, it is disposed within the annular working portion of the diaphragm, between the walls thereof, with the convolutions of the spring slightly spaced from each other and lying generally normal to the walls and radially of the diaphragm. The diaphragm is desirably mounted for double action, in a casing which provides displacement chambers on its opposite sides, formed to give but small clearance space at the ends of the diaphragm strokes.

The mechanical diaphragm support can be used with any of various diaphragm materials, including flexible rubber or rubber-like materials, synthetic plastic materials, coated fabric or leather materials, etc. But the diaphragm-wall material need not be impervious to the liquid upon which it is to operate, and we prefer to use a simple tanned leather for the diaphragm, for example, chrome-tanned cowhide or calfhide. We find that in a pump for oil, gasoline, hydrocarbon fuels, and the like,

2

a spring-annulus supported leather diaphragm gives remarkably long life and operates effectively and efficiently over a wide range of temperatures down to —65° F.

The accompanying drawing illustrates our invention. 5 In such drawing, Fig. 1 is a vertical axial section through a double acting diaphragm pump embodying our invention; Fig. 2 is an enlarged partial section similar to that of Fig. 1; and Fig. 3 is a plan view of a diaphragm embodying our invention, with parts of the upper wall broken 10 away to show the supporting coil spring.

The pump shown in Fig. 1 comprises a front casing 10, a rear casing 12 symmetrical with the front casing, a bottom intake fitting 13 and a top discharge fitting 14, with valve plates 16 mounted between each fitting and the 15 casings 10 and 12 have continuous annular flanges 15 between which the outer rim of the diaphragm assembly is clamped, and the casings from a front displacement space 18 and a rear displacement space 19 on opposite sides of the diaphragm assembly.

The two valve plates 16 are conveniently of identical 20 construction, held in place against opposite ends of the casing assembly by being clamped between it and the end fittings 13 and 14. Each valve plate 16 is punched and flanged to form two valve openings spaced to lie on 25 opposite sides of the casing flanges 15, and each bounded by an upstanding rim 20. The rims 20 are dressed to form planar valve seats, and flap valves 21 are seated on such valve seats. The valves 21 are carried by upstanding ears pivoted on pivots 22 mounted between lugs secured 30 to the plate 16, and the valves are urged to closed position by the down-turned ends of springs 23 coiled about the pivot pins 22. Conveniently, the valve openings are of generally oval cross-sectional shape, and the section of Fig. 1 may be considered as taken on their minor axes.

35 With the valves arranged as shown, to open upwardly, the general direction of pumped flow will be upward, as to pump liquid out of a tank upon which the pump may be mounted. Alternatively, the valve plates 16 may be reversed, to open downward, in which case the general direction of pump flow will be downward, making the 40 pump suitable for mounting on a tank which is to be filled and for pumping liquid from an external supply into that tank. The pump may also be mounted horizontally, or in any convenient position.

45 The diaphragm assembly comprises a central piston portion and an annular working portion. The central piston is formed by a pair of circular plates 26 clamped against opposite sides of the central webs of two diaphragm elements 25. Each plate 26 is outwardly flanged at its edge, to stiffen it and to form a smoothly curved 50 support for the inner periphery of the working annulus of the diaphragm. The piston is mounted on the operating shaft 28, which is formed in two parts, screwed together against the opposite faces of the plates 26. The shaft 28 is mounted in bearings in the two casings and 55 extends outward through the front casing 10, where its outer end is connected to an operating lever 24 fulcrumed on a link 29 carried by the front casing.

The two diaphragm elements 25 are symmetrical. Each 60 has a central circular web 32, a formed annular working portion 34, and a peripheral rim 36 which has straight edges at the top and bottom where it approaches the flat valve plates 16. The annular working portion 34 is desirably molded or shaped to a normal configuration which is semi-circular in cross section, with a wall arc 65 length of substantially 180°, joined to the web 32 in a smooth curve conforming with the flanged edges of a plate 26.

The diaphragm elements shown were made of top grade, chrome-tanned cowhide, but other and poorer 70 grades of leather can also be used. The leather may be treated to render it impervious to the liquid upon which

it is to work, as by a suitable coating or impregnating, but for gasoline, oil, and the like, we prefer to use an untreated leather which is somewhat pervious to the liquid to be worked. For extreme low temperature operation, on gasoline and the like, untreated leather is by far the most satisfactory, indeed we have found nothing to equal it for operation at -65°F .

The two diaphragm elements 25 are assembled with their webs 32 between the piston plates 26, and with their rims 36 held between the flanges 15 of the casings. Their annular portions 34 lie in oppositely and outwardly convex positions, defining an annular space of substantially circular cross-section, and it is these annular portions which form the working annulus of the diaphragm assembly.

The opposite walls of the working annulus are mechanically supported from each other. The mechanical supporting means is desirably a formed wire assembly having considerable resistance to compression diametrically of the annulus section but desirably being extensible circumferentially of the annulus. Preferably, it is of circular cross section, with a somewhat smaller section diameter than the internal section diameter of the working annulus. It may be either under compression circumferentially, so that it tends to hug the outer peripheral walls of the working annulus, or preferably is under tension, so that it tends to hug the inner periphery of those confining walls. We consider it most desirable to make the mechanical supporting means as shown, as a simple helical spring 39, with straight convolutions bent in a single plane.

The section diameter of the spring is desirably about 70% to 85% of the internal section diameter of the working annulus, and we have found it most suitable to use a spring with a section diameter about 75% of that of the working annulus. The coil spring is desirably made of fine spring wire with a large number of turns, and the opposite ends of the spring are secured together as bylapping one or two turns and welding or soldering the lapped turns together, as at the spots 31. Alternatively, the ends may be mechanically interlocked. The complete ring should have no free ends liable to puncture the diaphragm walls.

With a working annulus of 1-inch section diameter, we have found it desirable to use a coil of about .75 inch diameter wound from .040-inch spring wire, approximately 14 turns to the inch, and to use about 265 turns for the complete ring. The ring so formed is of somewhat smaller internal diameter than the internal diameter of the working annulus so that the spring will be stretched somewhat when in operative position and normally lies against the piston-side of the working annulus. A ring made as set forth above has an unstressed internal diameter of about $3\frac{1}{2}$ inches, and was used in a diaphragm whose piston was of about 4-inch diameter.

The wire from which the spring is made should be of a material not subject to attack by the fluid upon which the diaphragm is to work, and for a gasoline pump we have found it suitable to use a stainless-steel or preferably Phosphor-bronze spring wire.

The displacement spaces 18 and 19 in the casings 10 and 11 are formed to provide small clearance at the ends of the strokes of the diaphragm assembly. To this end, the central areas 38 of the end walls of the displacement spaces are flat to conform to the flat areas of the plate 26, and are bounded by grooves 39 into which the flanges of the plate 26 may move. Outward from these grooves 39, opposite the working annulus of the diaphragm, the walls 40 are curved to mate with the walls of the working annulus at the ends of the strokes. The displacement spaces thus defined communicate with the valves through passageways of limited cross-section and volume, which extend generally radially of the pump, in the plane of the section shown in Fig. 1.

With the pump assembled as indicated and as shown and with the intake fitting 13 connected to a source of

liquid, reciprocation of the operating shaft 28 through strokes in opposite directions produces a double-acting pumping effect. As the shaft 28 moves to the right, it carries the central piston bodily to the right and flexes the working annulus of the diaphragm. This increases the volume of the rear displacement space 19, to draw liquid into that space through the (lower left) valve between the intake fitting 13 and the rear displacement space 19. Simultaneously, the front displacement space is reduced in volume, to discharge liquid therein through the (upper right) valve between that displacement space 18 and the discharge fitting 14. A corresponding action occurs upon the opposite stroke of the shaft 28, to draw liquid into the displacement space 18 through its associated intake valve, and to discharge liquid from the displacement space 19 through its associated discharge valve.

During such operation, the leading wall 34 of the working annulus is in contact with liquid under pressure. In the absence of support, that wall would collapse and would be reverted from a forwardly convex form to a concave form. Such collapse is prevented, however, and the wall is supported in constantly convex position by the mechanical support of the internal spring 39. The force on the leading wall is transmitted diametrically across the spring section and against the trailing wall 34. This trailing wall being normally inelastic and already positioned in a trailing arc between the fixed support of the flanges 15 and the moving support of the pistons, supports the spring and carries the load reaction. When the stroke is reversed, the wall 34 which has been the leading wall then becomes the trailing wall. Since there was no wall reversion, the new-trailing wall is already in a trailing arc position—ready to pick up the load reaction, with little or no lost motion. The reverse stroke is effective at once, and proceeds under the same load transmission and load reaction conditions, in a reverse direction, as existed on the forward stroke. In both stroke directions, the load is carried by a wall which is not only pre-positioned to receive it, but by one which is in a most favorable position to carry it.

The use of diaphragm materials which are pervious to the liquid being pumped has not been found harmful to the operation or efficiency of a pump embodying the invention, and on the contrary has certain advantages. The liquid serves to lubricate the diaphragm and accumulates within the working annulus to keep the diaphragm moist and pliable during intervals of non-use. On long or frequent pumping operations, the liquid may fill the working annulus sufficiently to provide additional mutual support between the opposite walls.

Pumps having our mechanical supporting means for the diaphragm walls have been found to give a remarkably long service life, exceeding by six to ten times the service life of certain rubber-diaphragm pumps of similar construction.

We claim as our invention:

1. A pump diaphragm assembly, comprising a working annulus extending between an outer peripheral rim and a central piston adapted to be reciprocated axially with respect to the rim, said annulus comprising opposite outwardly convex walls of flexible material defining a space of substantially circular cross-section, and an endless helical spring ring within said space and of smaller cross-section than said space and said spring being substantially incompressible across its section, extending circumferentially around said annulus between said annulus walls and the turns of said spring being spaced from each other and contacting each wall in a substantially circular series of points so that said ring will stretch and contract along its helical axis and will provide mutual support between the walls during reciprocation of said piston relative to said rim.

2. A pump diaphragm assembly, comprising a working annulus extending between an outer peripheral rim and a central piston adapted to be reciprocated axially with

respect to the rim, said annulus comprising opposite outwardly convex walls of flexible material defining a space of substantially circular cross-section, and an endless helical spring ring within said space and of smaller cross-section than said space and said spring being substantially incompressible across its section, extending circumferentially around said annulus between said annulus walls and the turns of said spring being spaced from each other and contacting each wall in a substantially circular series of points so that said ring will stretch and contract along its helical axis and will provide mutual support between the walls, said spring ring comprising a multiplicity of closely spaced turns wound from small-gauge spring wire and providing a relatively rigid support for said walls in a cross-sectional direction while freely undergoing rolling deformation as the inner and outer peripheries of said annulus are reciprocated relative to each other.

3. A pump diaphragm assembly as defined in claim 1 in which the section diameter of said helical spring is between 70% and 85% of the diameter of the circular cross-section of the space between the annulus walls.

4. A pump diaphragm assembly as defined in claim 2 in which the section diameter of said helical spring is about 75% of the diameter of the circular cross-section of the space between the annulus walls.

5. A pump diaphragm assembly for pumping oil, gasoline, hydrocarbon fuels, and the like, comprising a working annulus extending between an outer peripheral rim and a central piston adapted to be reciprocated axially with respect to the rim, said annulus comprising opposite outwardly convex walls defining a space of substantially circular cross-section, and a helical spring ring of smaller cross-section than said annulus extending circumferentially around said annulus between said annulus walls and providing mutual support therebetween during relative reciprocation of said piston, said annulus walls being composed of material which is pervious to the liquid to be pumped whereby said walls are saturated by such liquid during operation and the interfaces between said walls and spring are lubricated thereby.

6. A pump diaphragm assembly for pumping oil, gasoline, hydrocarbon fuels, and the like, comprising a working annulus extending between an outer peripheral rim

and a central piston adapted to be reciprocated axially with respect to the rim, said annulus comprising opposite outwardly convex walls defining a space of substantially circular cross-section, and a helical spring ring of smaller cross-section than said annulus extending circumferentially around said annulus between said annulus walls and providing mutual support therebetween during relative reciprocation of said piston, said annulus walls being composed of material having limited permeability by the liquid being pumped, whereby on continuous operation the space between said walls becomes filled by said liquid to provide additional mutual support between said walls.

7. A pump diaphragm assembly for pumping oil, gasoline, hydrocarbon fuels, and the like, comprising a working annulus extending between an outer peripheral rim and a central piston adapted to be reciprocated axially with respect to the rim, said annulus comprising opposite outwardly convex walls defining a space of substantially circular cross-section, and a helical spring ring of smaller cross-section than said annulus extending circumferentially around said annulus between said annulus walls and providing mutual support therebetween during relative reciprocation of said piston, said annulus walls being composed of leather which is permeable by the liquid being pumped, whereby said leather walls are maintained pliant and the interfaces between said walls and spring are lubricated by such liquid.
